UNITED STATES PATENT OFFICE.

LINZIE A. GARDINER, OF DRY RIDGE, KENTUCKY.

ROAD-BUILDING MACHINE.

Application filed March 3, 1922. Serial No. 540,676.

To all whom it may concern:

Be it known that I, LINZIE A. GARDINER, a citizen of the United States, residing at Dry Ridge, in the county of Grant and 5 State of Kentucky, have invented certain new and useful Improvements in Road-Building Machines, of which the following is a full, clear, and exact description.

My invention relates to machines for 10 building or resurfacing roads, and has for its object to provide such a device with a stone crusher and a self-feeder, whereby the stones are readily reduced to the proper size.

A further object of the invention is the 15 use of a screen for separating the crushed stone of the desired size from the smaller stones, and also to provide means for conveying the smaller stones or screenings to the side of the road, and other means for 20 carrying the larger stones to the rear of the machine.

Another object of the invention is the provision of a spreader drawn by the apparatus and into which the stone is fed; the spreader 25 being vertically adjustable so that the stone may be laid to the required depth.

Other objects and advantages of the invention will be apparent from the following description when taken in connection with 30 the accompanying drawing, in which:

Figure 1 is a side elevation of the machine in operation.

Figure 2 is an enlarged vertical section through the machine.

Figure 3 is a front end view of the machine.

Figure 4 is a fragmentary plan view of the machine, showing details of the stone crusher.

40 Figures 5 and 6 are perspective views of details of the stone crusher.

Figure 7 is a section through the auxiliary stone crusher.

Figure 8 is a fragmentary rear view of 45 the machine, showing the means for conveying the screenings to the side of the road.

Figure 9 is a detail plan view of the adjustable chute for the screenings.

Figure 10 is a detail side elevation of 50 means for adjusting the chute shown in Figures 8 and 9.

Figure 11 is a fragmentary side elevation of a conveyer and spout.

Figure 12 is a rear view of the apparatus 55 partly in section.

Figure 13 is a fragmentary sectional view through one end of the screen.

Figure 14 is a detail view of a clutch mechanism.

Figure 15 is a side elevation of the screen 60 detached from the machine, and showing its different positions in dotted lines.

Figure 16 is a section through the screen.

Figures 17 and 18 are detail views of means for adjusting the screen.

Figure 19 is a side elevation of a spreader 65 used in connection with the stone crusher.

Figure 20 is a plan view of the spreader.

Figure 21 is a longitudinal section through the spreader.

Figure 22 is a transverse section taken on line 22—22, Figure 20, and

Figure 23 is a transverse section taken on line 23—23, Figure 20.

Referring to the drawing more in detail, 75 the numeral 1 designates the tractor to which is attached the spreader 2 by means of the cable 3.

Mounted on the forward end of the tractor 1 is a stone crusher which comprises a 80 pair of jaws 4 and 5, the jaw 4 being rendered adjustable by means of the wedge-shaped member 6, slotted plate 6^a, and screw 7. The jaw 5 is pivotally mounted at 8, and is oscillated on its pivot by means of the 85 eccentric rod 9 and eccentric 10^a on shaft 10. Just below the jaws 4 and 5 I have provided a shaft 11 on which is mounted the steel sleeve 12 formed with the radially extending fingers 13. The sleeve 12 is secured to 90 the shaft 11 by means of the key 14 and setscrew 15, the purpose of this shaft and fingers being to break up any stones which are too small to be engaged by the jaws 4 and 5.

The stone to be crushed is loaded onto the self-feeder which comprises a belt 16 on which are mounted the cleats 17. The belt 16 is operated over the rollers 19. The self-feeder may be raised or lowered, and to this end I have provided the curved slots 100 22 which receive the lower ends of the supporting rods 23; the rods 23 being clamped in the desired adjusted position by means of the locking screws 24.

Below the stone crusher are mounted the 105 hopper 28 and chute 29 which convey the crushed stone to the screen 30. The screen 30 comprises the two telescoping cylindrical members 31 and 32 formed with the openings 33 and 34, respectively. The cylinders 110

31 and 32 are movable relatively in order to vary the amount by which the openings 33 and 34 overlap, or to move these openings entirely out of register. In order to 5 adjust the cylinders 31 and 32, I employ a lever 35 pivoted to the frame of the apparatus at 36, and having its formed end 37 provided with rollers 38 which engage a flange 39 on the outer cylinder 32. A latch 10 40 is carried by the lever 35 to lock the screen in its adjusted position. On the interior of the screen is located a shaft 41 on which are mounted the propellers or agitators 42 for agitating the stone delivered 15 to the screen and advancing the same along the screen to the rear of the machine. To aid in the movement of the stone along the screen, especially when the apparatus is working on a hill, it is of importance that 20 the rear end of the screen should be vertically adjustable, and to this end I have provided the shaft 43 which is screw threaded on the frame, as shown at 44, and is swivelly connected to the shaft 41. By 25 means of the crank or wheel 45 the shaft 43 is operated to raise or lower the shaft 41, and likewise the screen which is supported on the shaft by the spiders 46.

Below the screen 30 is a trough 50 which 30 receives the powdered stone escaping through the openings 33 and 34 of the screen. A screw conveyer 51 is mounted in the trough 50 and moves the screenings to the rear end thereof, where they are received in the buckets 52 on the endless chain 53, which is operated by means of sprocket wheels 54 and 55 driven by sprocket 55^a on the shaft of the screw conveyer 51. A hood 56 envelops the upper end of the conveyer 40 and aids in directing the screenings into a chute 57. The chute 57 is preferably rendered extensible by the use of two sections 58 and 59, the latter being provided with a rack 60 and the former carrying a pinion 45 61 in mesh with the rack. The pinion 61 is rotated by means of a crank 62 and is held in the desired position by means of the pawl and ratchet 63 and 64. The conveyer 53 is supported from the frame of the machine by means of the arms 65 which are hinged at 66 in order that when moving 50 the machine the conveyer may be moved into a substantially vertical position by swinging the upper end toward the machine 55 and may be held in such position by the hook and eye 67 and 68, or other suitable fastening means.

Stones which are too large to pass through the perforations 33 and 34 pass through the 60 open end 70 of the screen and gravitate to the bottom of chute 71, where they are picked up by the buckets 72 of the conveyer 73 and dropped into the pivoted chute 74. The conveyer 73 is operated by means of 65 the sprockets 75, the upper end of the con-

veyer being enclosed by the hood 76 which is supported from the main framework of the apparatus by means of the adjustable arms 77.

The motive power for moving the machine and also for operating the various parts of the mechanism consists of a motor 80 mounted on the top of the framework of the machine and geared to the wheels 81 by means of chains 82 or other form of gearing. The self-feeder 16 is operated from the motor by means of the belt 83 and pulley 19. Chain 84 transmits power from the motor to the sprocket 84^a and shaft 11 which forms the auxiliary stone crusher. A belt 85 is mounted on the pulley 86 on the shaft 10. Pulley 86 also transmits power to the conveyer 73 by means of the sprocket wheel 86^a and chain 87. Shaft 10, by means of the bevel gears 90 and 91, operates 85 the vertically extending shaft 92, which, through suitable worms 93-94 and worm wheels 95 and 96, operates the shaft 98, which is connected by the universal joint 99 with the shaft 41, and also operates the 90 shaft 100, which is rigidly connected to the screw conveyer 51.

In order that the self-feeder may be thrown out of operation in the event that the stone crusher becomes jammed, or for any other reason, I have provided the clutch 101 for disconnecting the motor from the various mechanisms. This clutch is operated by means of the bell-crank lever 102 pivoted to the framework of the machine, as shown at 103, and normally held in operative position by the spring 104.

The spreader 2 which is drawn by the apparatus by means of the cable 3 is a substantially rectangular member having each 105 of its sides formed of two members 110 and 111, adjustable vertically by means of the slot and bolt connection 112 and 113. The lower members 110 are provided with metal runners 114 formed with inwardly extending flanges 115. The purpose of the flanges 115 is to engage under the crushed stone and thereby hold the spreader down in its proper position. The rear end of the spreader is composed of two members 116 and 117 adjustably connected by means of the slots 118 and bolts 119. By means of the adjustments just described the stone may be laid to any depth desired and will be leveled off to the proper depth by means of the adjustable cross member 117.

In operation, the screen 30 and spreader 2 are adjusted to the proper positions for the immediate work to be done. As the clutch is let in the various mechanisms will be put in operation, the stone which is loaded onto the self-feeder being carried to the crusher, and thence through the screen 30. After passing through the screen the screenings or finer material is carried to the side of the 120 125 130

road by the buckets 52, while the larger stones are carried by the conveyer 73 and chute 74 to the spreader 2, which spreads the stone in a uniform layer to the depth for which it is adjusted.

In accordance with the patent statutes, I have described what I now believe to be the best embodiment of the invention, but I do not wish to be understood thereby as limiting myself or the scope of the invention, as many changes and modifications may be made without departing from the spirit of the invention; all such I aim to include in the scope of the appended claims.

What I claim as new and desire to secure by Letters Patent is:

1. A road building machine including a vehicle, a stone crusher mounted thereon, a conveyor extending from the stone crusher to a point beyond the body of the machine, means for permitting vertical adjustment of one end of the conveyor, a screen extending longitudinally of the vehicle and cooperating with said stone crusher and adapted to separate the material into two grades, means for raising and lowering one end of said screen, a spreader, means for conveying one grade of material into the spreader, and means for conveying the other grade of material to the side of the road.

2. A road building machine including a vehicle, a stone crusher mounted thereon,

means for conveying stone to the crusher, a screen extending longitudinally of the vehicle and cooperating with said stone crusher and adapted to separate the material into two grades, means for raising and lowering one end of said screen, a spreader, means for conveying one grade of material to the spreader, and means for conveying the other grade of material to the side of the road.

3. A road building machine including a vehicle, a stone crusher mounted thereon, a screen extending longitudinally of the vehicle and cooperating with said stone crusher, means for raising and lowering the rear end of the screen, means for conveying a portion of the screened material to the road, and other means for conveying another portion of the screened material to one side of the road.

4. A road building machine including a vehicle, a stone crusher mounted thereon, a screen extending longitudinally of the vehicle and cooperating with said stone crusher and adapted to separate the material into two grades, means for raising and lowering one end of the screen, a conveyor projecting rearwardly from the vehicle, and a chute cooperating with said conveyor and adapted to direct the conveyed material to selected positions on the roadbed.

LINZIE A. GARDINER.
